J. HAMILTON BROWN, OF WATERTOWN, MASSACHUSETTS.

Letters Patent No. 60,681, dated January 1, 1867.

IMPROVEMENTS IN HAND PEGGING MACHINES.

The Schedule referred to in these Letters Patent and making part of the same.

TO ALL WHOM IT MAY CONCERN:

Be it known that I, J. HAMILTON BROWN, of Watertown, in the county of Middlesex, and State of Massachusetts, have invented certain Improvements in Pegging Machines, of which the following is a full, clear, and exact description, reference being had to the accompanying drawings, making part of this specification, in which—

Figure 1 is an elevation of a hand pegging machine with my improvements applied thereto.

Figure 2 is a plan of the under side of the same.

Figure 3 is a vertical section on the line $x\ x$ of fig. 2, the plunger being shown depressed.

Figure 4 is a vertical section on the line $y\ y$ of fig. 2, the plunger being raised.

Figure 5 is a horizontal section on the line $z\ z$ of fig. 1.

Figures 6, 7, 8, and 9, details to be referred to.

In hand pegging machines of the ordinary construction, where the spring which raised the plunger was placed around outside of it, the diameter of the lower portion of the plunger was reduced to accommodate the spring, and consequently but a small portion of the surface of the plunger had any bearing against the interior surface of the shell or casing which surrounded it, and the violent jarring occasioned by the blow of the hammer caused the plunger and parts secured thereto to have a lateral play, which frequently resulted in their being deranged or broken.

To overcome the above-mentioned difficulties, and to produce a durable, compact, and reliable machine, is the object of my invention, which consists in a hollow plunger, within which is placed the spiral spring by which it is raised after its downward stroke, while within its exterior are formed grooves or channels of varying depth for the reception of the levers which regulate the motions of the knife and feeding-point, by which construction the surface of the plunger through nearly its whole length may have a bearing upon the interior of the shell or casing, and the plunger and parts connected therewith are not liable to "jar off," the knife being so connected by its lever to the plunger that one peg only is cut off on the commencement of the downward stroke of the plunger at the instant preceding the descent of the driver to force it into the hole last made by the awl, whereby the clogging incident to cutting several pegs in advance, or one peg by the upward stroke of the knife, is avoided, while the lever which operates the feeding-point through its connection with the plunger causes the point to rise and advance, to fall, and recede, in such manner that the feed of the machine over the sole is accomplished with a greater degree of certainty than with those of the old construction. My invention also consists in certain devices for varying the distance of the pegs from the edge of the sole, and for keying the awl and peg-driver to the plunger, which will be set forth hereafter.

To enable others skilled in the art to understand and use my invention, I will proceed to describe the manner in which I have carried it out.

In the said drawings, A is the shell or casing of the instrument, which is grasped by the hand when ready for use. B is a trough for holding the strip of peg wood, α , which is fed forward to be cut into pegs by the follower C and rubber spring D. The trough is secured to near the bottom of the casing A by a screw, and is open at both ends, at its outer end for the purpose of inserting the peg wood, and at its inner end to allow the wood to be pressed up against the casing so as to lie in the path of the knife E sufficiently far to insure the cutting of a single peg immediately on the commencement of the downward stroke of the piston or plunger F, to the lower end of which are secured by a pin, 12, (see fig. 3,) the peg-driver δ and awl e , at a distance apart equal to that between two pegs, suitable passages for the awl and driver being provided in the bottom of the casing to allow them to slide freely therein. The plunger is made hollow for the reception of a spiral spring, d , which is confined therein by a head, G, which screws over the upper end of the plunger, the lower end of the spring resting upon a pin, H, which passes through rectangular slots, e , formed in the plunger, and also passes into the shell or casing for the purpose of preventing the revolution of the plunger within it. The awl is driven into the shell or casing for the purpose of preventing the revolution of the plunger within it. The awl is driven into the leather, and the pegs into the holes made by the awl, by a blow of a hammer upon the head of the plunger, and the awl is extracted from the leather by the recoil of a rubber spring, I, placed immediately beneath the head of the plunger after the spring has been compressed between the head and top of the casing by a blow from the hammer. The cavity in the plunger for the reception of the spring is made eccentric so that sufficient

space may be had on the outside of the plunger to allow a portion, 10, thereof to be planed down to serve as a path for the upper end of a lever, J, which is pivoted to the casing at f, and swings freely in a vertical slot or opening, g, cut therein, and by means of which the knife E is operated. The motion of the machine along the edge of the sole for the purpose of spacing the distances between the pegs is accomplished by a feeding-point, h, in the following manner: K is a lever of the form seen in section, fig. 3, which is pivoted at i to the casing, within which is formed a vertical slot, j, to allow of the play of the lever therein, the surface of the outside of the plunger being provided with a groove or channel, k, in which bears the upper end of the lever K, which is moved out and in by the rising and falling of the plunger. The lower end of the lever K terminates in a projection, l, which fits into a notch, m, formed in the heel of the curved arm or feeding-point h, which is pivoted loosely at n to a block or table, L, (of the form seen in fig. 7,) which is moved in and out of a recess, o, formed between the lower end of the casing and the plate M, which rests on the sole, the bottom of the table being provided with a spring, p, to insure the necessary friction of the parts when the table is acted upon by the lever K. The feeding-point is so actuated that on the rising of the plunger F it shall first be tipped downward and then carried forward with the table by the projection l on the lower end of the lever K until it enters the hole last made by the awl, and then, by the continued upward motion of the plunger, be fed along so as to bring the peg and peg-driver b directly over the hole, leaving it ready to be occupied by the peg, and is then carried back out of the way of the awl c, which now descends with the driver to make a new hole simultaneously with the driving of the last and only peg cut, and on the plunger again rising, the feeding-point enters the new hole and feeds the machine along. The details of the movements of the parts by which the feed is operated are as follows: The feeding-point, as before stated, is operated by the lever K, the lower end of which, when the plunger is up, is pressed inward, carrying the feeding-point into the hole immediately below the peg and peg-driver. On the plunger commencing to descend, the lower end of the lever K is pushed out, raising and retracting the feeding-point, and driving the awl into the sole to make a hole. On the plunger commencing to ascend, the lever K is vibrated so as to throw the feeding-point into the hole in advance, just made by the awl; and on the plunger still continuing to rise, the shell or casing is caused to rock forward on its pivot, i, carrying the plunger with the awl and peg-driver, the awl being now in a position to make the next hole ahead, and the driver just over the aperture 11, which contains the peg wood ready to be cut by the knife, to sever a peg therefrom in a manner which will now be described. The peg wood extends into this aperture, 11, and on the commencement of the downward stroke of the plunger, the upper end of the lever J is thrown out, while the lower end, to which the knife E is pivoted, is carried in, causing the knife to be pressed against the peg wood, cutting off a portion equal to the width of a single peg, which is retained by the knife in the aperture 11, immediately over the hole in the sole and under the peg-driver. N is a flat spring secured to the peg trough for throwing the knife back to allow the peg wood to be fed into the aperture 11. O is the gauge which rests against the edge of the sole and determines the distance which the pegs are put from the edge. This gauge is provided with a shank or spindle, P, the lower portion of which is of a rectangular form, and fits snugly within an aperture of corresponding form made in the plate M, while the remaining portion, r, of the shank is of a cylindrical form, and extends up into a cavity within the casing. Through the upper portion of the shank passes a pin, s, underneath which bears the top of a spiral spring, t, which surrounds the cylindrical portion of the shank, the bottom of the spring resting upon the upper side of the plate M, by which construction the gauge is prevented from turning when adjusted for use. The foot of the gauge is so formed that no two of its sides are the same distance from the line of the holes made by the awl, in order that it may be used for gauging the lines of the inner and outer rows of pegs from the edge of the sole, and for varying their distance, if desired. When it is required to make the holes only, to be afterwards filled with pegs or metallic nails, it is simply necessary to check the advance of the peg wood.

Operation.

The peg trough B being supplied with the peg wood in a manner before explained, the operator grasps the casing of the machine, and having first made a hole in the sole, places the feeding-point therein, the gauge resting against the edge of the sole and determining the position of the line of holes to be made with the awl. A blow is now given to the plunger, when a portion of the peg wood is first cut off by the knife to form a peg, which is struck by the driver and forced into the hole previously occupied by the feeding-point, the awl making a new hole, from which it is extracted by the rubber spring I, after which the pressure of the spring d continues to carry up the plunger, when the feeding-point enters the hole last made by the awl, and then continues its motions, as already described, carrying the machine with it a distance equal to that between two pegs. A second blow is now given, by which the feeding-point is first withdrawn from the hole in the sole, and then retracted out of the path of the awl and peg-driver, the knife, on the commencement of the downward stroke of the plunger, splitting off a peg and retaining it in the aperture 11 till struck by the driver at the latter end of the descent of the plunger. These operations are repeated by successive blows of the hammer on the plunger until the pegging is completed.

Claim.

What I claim as my invention, and desire to secure by Letters Patent, is—

The plunger F, made hollow for the reception of the spring d, substantially as and for the purpose set forth.

I also claim the plunger F, with its exterior surface so formed as to give to the lever J the required movements for causing the knife E to cut a single peg on the commencement of the downward stroke of the plunger, for the purpose specified.

I also claim the plunger F, with its groove k and exterior surface so formed as to cause the lever K to operate the feeding-point, substantially as set forth.

I also claim the table L, so formed that, in connection with the lever K, a uniform sliding and rocking motion, viz., down and forward, up and back, will be given to the feeding-point, for the purpose described.

I also claim the gauge-plate O, operated by its spring, t, and having the lower end, q, of its shank so formed as to fit snugly a slot of corresponding form in the plate M, by which it is prevented from turning therein when in use after adjustment, substantially as described.

I also claim the pin 12, or its equivalent, for performing the double office of keying the awl and peg-driver to the plunger, as set forth.

I also claim the removable head G, for confining the spring d within the plunger F, substantially as described.

J. HAMILTON BROWN.
